CLAIM

The ornamental design for a knife block, as shown and described.

DESCRIPTION

FIG. 1 is a top, front perspective view of a knife block according to a first embodiment of our new design;

FIG. 2 is a second top, front perspective view thereof;

FIG. 3 is a front perspective section view thereof;

FIG. 4 is a front elevation view thereof;

FIG. 5 is a rear side elevation view thereof;

FIG. 6 is a right side elevation view thereof;

FIG. 7 is a left side elevation view thereof;

FIG. 8 is a top plan view thereof; and,

FIG. 9 is a bottom plan view thereof.

1 Claim, 8 Drawing Sheets
